TERMINAL HAVING LEVER CLAMPING MEANS TO SECURE A CONDUCTOR THERETO

William Pahal, East St. Louis, Ill., assignor to Leslie V. W. Schrader, Belleville, Ill.

Application November 15, 1948, Serial No. 60,095.

2 Claims. (Cl. 173—269)

1

This invention comprises novel and useful improvements in a detachable electrode holder and more specifically pertains to a novel clamping means for electrically and mechanically securing an electric conducting cable to an electrode holder.

The principal object of this invention is to provide an improved clamping means for mechanically and electrically connecting an electric cable to an electrode holder.

The principal feature of this invention resides in providing an electrically conductive sleeve secured to one of the jaws of a substantially conventional electrode holder together with improved clamping means for mechanically and electrically securing and electrically conductive cable in said sleeve.

A further feature of the invention resides in providing one of the jaws of an electrode holder clamp with a sleeve, said sleeve being slotted longitudinally of its length to receive a clamping lever, said clamping lever having a cam portion for frictionally and wedgingly engaging the electric conductor of an electric cable, for clamping the same to the interior surface of the sleeve in electrically conductive relation therewith.

A further feature of the invention resides in the provision of a clamping means for an electrode holder in accordance with the foregoing features, together with an insulating housing longitudinally slidable upon said sleeve for retaining the clamping lever in its clamping position, and for insulating the entire surface of the sleeve and lever.

These, together with various ancillary features and objects of the invention which will later become apparent as the following description proceeds, are attained by this device, a preferred embodiment of which has been illustrated by way of example only in the accompanying drawings, wherein:

Figure 1 is a side elevational view of a conventional electrode holder having the novel cable clamping means applied thereto;

Figure 2 is a side elevational view similar to Figure 1 but a part of the clamping means being indicated in section to show the interior construction thereof, the clamping lever being indicated in dotted lines in its open or releasing position, the insulating housing being omitted from the clamping device;

Figure 3 is a bottom plan view of the arrangement of Figure 2, the clamping lever being shown in its closed position, and with the insulating cover for the clamping device being omitted;

2

Figure 4 is a fragmentary vertical transverse sectional view through the device shown in Figure 1;

Figure 5 is a vertical transverse sectional detail view taken substantially upon the plane of the section line 5—5 of Figure 2; and

Figure 6 is a fragmentary elevational view of a portion of the insulating housing forming a part of this invention.

10. Referring now more specifically to the accompanying drawings, wherein like numerals designate similar parts throughout the various views, it will be seen that the numeral 10 indicates generally a conventional form of electrode holder consisting of upper and lower jaw members 12 and 14 respectively which are pivoted together for relative movement towards and from each other for clamping an electrode therebetween. The upper jaw member is provided with an operating handle 16, and a suitable resilient means, not shown, is received within a housing 18 whereby the two jaws are biased towards each other for yieldingly clamping an electrode therebetween. The lower jaw 14 is provided with an operating handle or shank 20, and it is to this handle that the clamping device of this invention is to be applied.
15. 20. 25.

20. 25. 30. 35.
  30. 35. 40.
- This clamping device preferably consists of a metallic sleeve 22 which is immovably secured to the shank 20 in any desired manner, the two ends of the sleeve being preferably open. Within the open outer end of the sleeve 22 is received an insulation-covered electric cable 24, having an electrical conductor at its center, the end of which is shown at 26, this end being adapted to be pressed or wedged by a mechanism to be subsequently described into a mechanically secure and electrically efficient contact with the inner walls of the sleeve 22, wherebv current supplied by the cable 24 may be transmitted to the lower jaw 14 of the electrode holder 10.

35. 40. 45.
  45. 50.
- As seen clearly in Figures 2 and 3, the bottom or lower surface of the sleeve 22 is provided with a longitudinally extending slot 28 through any desired portion of the length of the sleeve, but preferably extending to the outer end thereof. A clamping lever 30, shown in dotted lines in its open position in Figure 2 at 32, is pivotally mounted in the sleeve 22 and is swingable into and out of the slot 28.

50. 55.
- This lever, as shown in Figure 5, is mounted between a pair of cylindrical segments 34 and 36, and is secured thereto as by a pivot pin 38, which extends through apertures 40 in the side wall of the sleeve 22, through the segments 34

and 36, and through the enlarged cam portion 42 of the lever 32.

The cylindrical segments 34 and 36 thus snugly fit the inside, cylindrical wall of the sleeve 22, embrace the lever portion 42 therebetween, and serve to provide a restricted chamber 44, see Figure 5, in the sleeve 22 for receiving the end portion 26 of the electric cable.

The wedging portion 42 of the lever 32 constitutes a cam, and is preferably provided with a plurality of serrations or teeth 46 which as shown in full lines in Figure 2 are adapted to be wedged into the sides of the terminal portion 26 of the cable, for tightly gripping the same, and establishing an electrical contact therewith.

It will now be seen that when the cable has been inserted into the open sleeve 22, the lever 30 being in its dotted line open position 32, the lever may then be pressed inward to its closed position as indicated by the arrow 48, whereby the teeth or serrations 46 of the cam portion 42 of the lever will tightly grip and retain the cable.

In order to properly insulate the clamping device, and retain the lever in its closed position, there is provided an insulating housing 50 which is preferably in the form of a sleeve or bushing of suitable insulating material, and which is longitudinally slidable upon the sleeve 22 from the cable end thereof. This bushing, as shown in Figures 1 and 4, is adapted to substantially snugly embrace the sleeve 22, and lever 30 when the latter is in its closed position, thereby preventing opening of the lever, and releasing of its electric and mechanical connection with the cable 24.

The outer end of lever 30 has a depending flange 52 and the end of the bushing 50 is radially notched or slotted at 54 to receive the flange therein. Thus the pull of the cable 24 on the toothed end 42 will tend to urge the lever to its open position whereby the flange 52 will be retained in slot 54. By this means, the lever holds the insulator in position, while the latter insulates and retains the lever in closed position.

From the foregoing, the construction and operation of the device will be readily understood and further explanation is believed to be unnecessary. However, since numerous modifications and changes will readily occur to those skilled in the art after a consideration of the foregoing specification and accompanying drawings, it is not desired to limit the invention to the exact construction shown and described, but all suitable modifications and equivalents may be resorted to, falling within the scope of the appended claims.

Having thus disclosed and described the invention, what is claimed as new is as follows:

1. An electrical connector for use with an electrode holder comprising, an elongated electrically conductive sleeve for receiving an insulated conductor in one end thereof, said sleeve having

5 a longitudinally extending slot therein, a pair of cylindrical segments disposed in the sleeve in spaced relation to said one end of the sleeve and in spaced and opposed relation to each other, a clamping lever normally extending longitudinally of the sleeve and disposed in the slot, a wedge portion on the lever adjacent one end thereof slidably projecting into the space between the segments to clamp the bared end of a conductor, a pivot pin extending through the sleeve, the segments and the wedge portion so that the lever may be swung outwardly from the sleeve to partially withdraw the wedge portion from between the segments, and an elongated removable electrical insulating hand grip surrounding the sleeve and retaining the lever against outward swinging movement.

2. An electrical connector for use with an electrode holder comprising, an elongated electrically conductive sleeve for receiving an insulated conductor in one end thereof, said sleeve having a longitudinally extending slot therein, a pair of cylindrical segments disposed in the sleeve in spaced relation to said one end of the sleeve and in spaced and opposed relation to each other, a clamping lever normally extending longitudinally of the sleeve and disposed in the slot, a wedge portion on the lever adjacent one end thereof slidably projecting into the space between the segments to clamp the bared end of a conductor, a pivot pin extending through the sleeve, the segments and the wedge portion so that the lever may be swung outwardly from the sleeve to partially withdraw the wedge portion from between the segments, and an elongated removable electrical insulating hand grip surrounding the sleeve and retaining the lever against outward swinging movement.

20 3. An electrical connector for use with an electrode holder comprising, an elongated electrically conductive sleeve for receiving an insulated conductor in one end thereof, said sleeve having a longitudinally extending slot therein, a pair of cylindrical segments disposed in the sleeve in spaced relation to said one end of the sleeve and in spaced and opposed relation to each other, a clamping lever normally extending longitudinally of the sleeve and disposed in the slot, a wedge portion on the lever adjacent one end thereof slidably projecting into the space between the segments to clamp the bared end of a conductor, a pivot pin extending through the sleeve, the segments and the wedge portion so that the lever may be swung outwardly from the sleeve to partially withdraw the wedge portion from between the segments, and an elongated removable electrical insulating hand grip surrounding the sleeve and retaining the lever against outward swinging movement.

25 4. An electrical connector for use with an electrode holder comprising, an elongated electrically conductive sleeve for receiving an insulated conductor in one end thereof, said sleeve having a longitudinally extending slot therein, a pair of cylindrical segments disposed in the sleeve in spaced relation to said one end of the sleeve and in spaced and opposed relation to each other, a clamping lever normally extending longitudinally of the sleeve and disposed in the slot, a wedge portion on the lever adjacent one end thereof slidably projecting into the space between the segments to clamp the bared end of a conductor, a pivot pin extending through the sleeve, the segments and the wedge portion so that the lever may be swung outwardly from the sleeve to partially withdraw the wedge portion from between the segments, and an elongated removable electrical insulating hand grip surrounding the sleeve and retaining the lever against outward swinging movement.

30 5. An electrical connector for use with an electrode holder comprising, an elongated electrically conductive sleeve for receiving an insulated conductor in one end thereof, said sleeve having a longitudinally extending slot therein, a pair of cylindrical segments disposed in the sleeve in spaced relation to said one end of the sleeve and in spaced and opposed relation to each other, a clamping lever normally extending longitudinally of the sleeve and disposed in the slot, a wedge portion on the lever adjacent one end thereof slidably projecting into the space between the segments to clamp the bared end of a conductor, a pivot pin extending through the sleeve, the segments and the wedge portion so that the lever may be swung outwardly from the sleeve to partially withdraw the wedge portion from between the segments, and an elongated removable electrical insulating hand grip surrounding the sleeve and retaining the lever against outward swinging movement.

35 6. An electrical connector for use with an electrode holder comprising, an elongated electrically conductive sleeve for receiving an insulated conductor in one end thereof, said sleeve having a longitudinally extending slot therein, a pair of cylindrical segments disposed in the sleeve in spaced relation to said one end of the sleeve and in spaced and opposed relation to each other, a clamping lever normally extending longitudinally of the sleeve and disposed in the slot, a wedge portion on the lever adjacent one end thereof slidably projecting into the space between the segments to clamp the bared end of a conductor, a pivot pin extending through the sleeve, the segments and the wedge portion so that the lever may be swung outwardly from the sleeve to partially withdraw the wedge portion from between the segments, and an elongated removable electrical insulating hand grip surrounding the sleeve and retaining the lever against outward swinging movement.

40 7. An electrical connector for use with an electrode holder comprising, an elongated electrically conductive sleeve for receiving an insulated conductor in one end thereof, said sleeve having a longitudinally extending slot therein, a pair of cylindrical segments disposed in the sleeve in spaced relation to said one end of the sleeve and in spaced and opposed relation to each other, a clamping lever normally extending longitudinally of the sleeve and disposed in the slot, a wedge portion on the lever adjacent one end thereof slidably projecting into the space between the segments to clamp the bared end of a conductor, a pivot pin extending through the sleeve, the segments and the wedge portion so that the lever may be swung outwardly from the sleeve to partially withdraw the wedge portion from between the segments, and an elongated removable electrical insulating hand grip surrounding the sleeve and retaining the lever against outward swinging movement.
